STEREOTYPE PLATE CASTING MECHANISM

Frank A. Foster, Maywood, Ill., assignor to The Goss Printing Press Company, Chicago, Ill., a corporation of Illinois

Application February 20, 1935, Serial No. 7,346

4 Claims. (Cl. 22—2)

The present invention relates to stereotype casting machines and more particularly to novel improvements in the molten metal reservoir of a stereotype casting machine.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, construction, arrangements, combinations and improvements herein shown and described.

15 The accompanying drawing, referred to herein and constituting a part hereof, illustrates one embodiment of the invention, and together with the description, serves to explain the principles of the invention.

20 Of the drawing:

Figure 1 is a side elevation of an illustrative embodiment of the present invention, certain parts being shown as broken away;

25 Figure 2 is a detailed sectional view of a part of the molten metal reservoir; and

Figure 3 is a sectional view taken on the line 3—3 of Figure 2.

The present invention has for its object the provision of a novel and improved stereotype 30 plate casting molten metal reservoir. Another object of the invention is the provision of a novel and improved means for controlling the flow of metal from the reservoir to the plate casting chamber in a stereotype casting machine.

35 The present embodiment of the invention is shown in connection with a stereotype plate casting machine of the type shown and described in the patent to myself and Charles H. Armstrong, No. 1,957,543 dated May 8, 1934, although the invention may be employed in connection with 40 many other types and forms of stereotype casting machines.

As shown in the prior patent referred to, the stereotype casting machine comprises a stereotype casting chamber 10 within which is received a stereotype matrix surrounding a cylindrical core 11, the chamber and core being mounted upon a reciprocable bed 12 which is movable to and fro along the bed rails 13 by rotation of the hand wheel 14. Attached to one end of the core 11 is a screw 16 supported in guides 17 within which the screw 16 and core 11 may be moved axially of chamber 10 by rotation of gear 18. A reservoir for molten metal is provided and comprises a 50 semi-spherical pot 20 supported on and within a

casing 21. Pot 20 is formed with a neck 22 leading to a tapered throat 23 which is positioned in alignment with core 11, so that molten stereotype metal may be supplied from the reservoir to the casting chamber.

5 Throat 23 is formed with an internally tapered bore and in accordance with the present invention, this throat is closed by means of a tapered plug-like member formed of resilient laminated material, such as thin spring steel and the individual laminations are sufficiently resilient so that the obstruction of one or more of them will not prevent proper seating of the remainder of them against the tapered inner face of the bore. As embodied, there is provided a threaded 15 pin 25, having a relatively large flanged head 26, positioned centrally of and axially aligned with the tapered bore of throat 23, flanged head 26 being only slightly smaller than the internal diameter of the bore. Assembled on pin 25 are a plurality of resilient, circular discs 27, all of these discs being of similar shape and differing only slightly from each other in size; the smallest disc being positioned closest to the mouth of the bore, and the other discs being successively larger. 20 Discs 27 are spaced apart from each other by smaller discs 28, also mounted on the pin 25, and the tapered assembly of discs 27 and 28 are firmly held in assembled relation by means of washer 29 and nut 30. Discs 27 are preferably slightly 25 dished and are positioned with their convex side towards the mouth of the bore.

Means are provided for guiding the discs 27 into closing position and for this purpose a plurality of narrow guiding members 32 are mounted on the washer 29 and extend rearwardly therefrom. These guide strips are preferably resilient, and are shaped to conform generally to the internal taper of throat 23.

35 Means are provided for moving the assembled discs 27 into and out of closing position within the throat 23 and for this purpose a bell crank or handle 40 is pivotally mounted in a bracket 41 on top of the molten metal reservoir. Handle 40 is connected with a lever 42, pivotally mounted in brackets 43, by means of a link 44, and lever 42 is, in turn, connected with pin 25 by means of links 46 which are pivotally connected to pin 25 by means of pivot bolt 48. Connected with the pivot pin between lever 42 and link 44 is a cable 50 running over pulley 51 which is rotatably supported on and above the molten metal reservoir. At the other cable 50 are suspended relatively heavy weights 53 which force the discs 27 40 tightly against the walls of the tapered bore.

When the operator desires to cast a plate, the casting chamber 10, core 11 and bed 12 are moved to the left (Fig. 1) until the core 11 is tightly seated within the beveled mouth of throat 23. 5 The operator then pulls down on handle 40 withdrawing the discs 27 from their tightly seated position within the bore of throat 23. Metal then flows from the molten metal reservoir through throat 23 into the casting chamber 10 until the 10 casting chamber has been filled with metal. The operator may then release handle 40 causing the weights 53 to move the discs 27 towards core 11 until the discs are all tightly seated against the internally tapered bore of throat 23. 15 Due to the relatively large number of discs 27 employed and to the spacing of these discs, a complete closure of the throat is always insured. The obstruction of one or more of the discs so 20 as to prevent its proper seating of that disc does not permit passage of molten metal past the other discs. The pressure of the molten metal against the convex sides of the discs tends to 25 force them outwardly and into tight contact with the bore. Furthermore, repeated heating and cooling of the stereotype metal within the molten metal reservoir does not result either in leakage 30 of the metal or in binding of the discs within the bore of throat 23, as the relatively thin resilient discs find their own seating regardless of the changing shape of the throat with temperature, 35 and the discs can never be held so tightly but that they can be easily dislodged by movement of the handle 40.

The invention in its broader aspects is not limited to the specific mechanisms shown and described but departures may be made therefrom within the scope of the accompanying claims without departing from the principles of the invention and without sacrificing its chief advantages.

What I claim is:

1. In a stereotype casting machine a metal supplying throat having an internally tapered, circular bore, and a closure in said bore comprising a plurality of thin, resilient metal discs of similar shape spaced from each other and in alignment, corresponding in size and shape to the bore of said throat, means for moving said discs to open and close said throat and resilient guide strips shaped to fit said bore, secured to said discs and extending therefrom into the molten metal. 5

2. In a stereotype casting machine, a throat for supplying metal from a reservoir to a plate casting chamber, said throat having an internally tapered, circular bore, and a closure in said bore comprising a pin extending axially of said bore and movable therein, a plurality of discs mounted in spaced-apart, aligned relation on said pin, all of said discs being of a size and shape to fit snugly against said bore, and each of said discs being slightly dished. 10

3. In a stereotype casting machine a throat for supplying metal from a reservoir to a plate casting chamber, said throat having an internally tapered, circular bore, and a closure in said bore comprising a pin extending axially of said bore and movable therein, a plurality of dished discs mounted in spaced-apart, aligned relation on said pin, all of said discs being of a size and shape to fit snugly against said bore and being assembled on said pin to form a tapered, laminated plug for said throat, and means for moving said assembled discs axially of said bore to open and close the throat. 20

4. In a stereotype casting machine, a throat for supplying metal from a reservoir to a plate casting chamber, said throat having an internally tapered bore, a disc-like closure near the exterior end of said throat and means for moving said closure to open and close the throat, including a rod-like member extending backwardly through the throat and leaving the greater part of the throat occupied by the molten metal in the reservoir. 35
